UNITED STATES PATENT OFFICE.

THOMAS D. CURRIE, OF PORT HURON, MICHIGAN, ASSIGNOR TO JOSEPH CASELLO, OF PORT HURON, MICHIGAN.

DISK-RECORD SHIPPER.

1,406,939.

Specification of Letters Patent. Patented Feb. 14, 1922.

Application filed June 3, 1920. Serial No. 386,204.

To all whom it may concern:

Be it known that I, THOMAS D. CURRIE, a citizen of the United States, residing at Port Huron, in the county of St. Clair and State 5 of Michigan, have invented certain new and useful Improvements in Disk-Record Shippers, of which the following is a specification.

The invention has for an object to effect 10 improvements in shipping packages for disk phonograph records, and aims to cheapen the manufacture thereof, and at the same time provide a safe and efficient article of the kind. It is also an aim to develop such 15 a container which will have specific features of improvement peculiar thereto.

Additional objects, advantages and features of invention will appear from the structure, arrangement and combination of 20 elements hereinafter described and shown in the drawings accompanying, in which—

Figure 1 is an elevational face view of a package constructed in accordance with my invention, with a portion broken away,

Fig. 2 is a vertical cross section thereof,

Fig. 3 is a view similar to Fig. 1 showing the device as used for shipping records in different sizes,

Fig. 4 is a cross sectional view vertically 30 of Fig. 3.

The shipper essentially includes front and back boards or plates 10 and 11 each of rectangular form, ordinarily made perfectly square, and of such size that their boundaries 35 will readily include the diameter of the largest record to be shipped, with a margin between the record and the edge of the plates. While the plates may be made of various materials, such as sheet metal, paste 40 board, and other materials, it is an especial advantage of my invention that very strong materials are not required such as heretofore used in shipping containers where plates have been clamped upon opposite 45 sides of one or more records, by means of screw and nut devices engaged axially with the record and container, and serving to hold the complete package in assembled form. In fact, paste board is preferably 50 used, and will enable the safe shipment of a considerable number of records, which may differ variously in size. Between the plates 10 and 11 there are interposed one or more spacer elements 12. These are each

of the same dimension externally as the 55 plates 10 and 11. The spacers 12 are substantially U-shaped in cross section, their bight portions being formed of such dimensions as will snugly accommodate particular sizes of records. The plate 11 is formed 60 with a tongue element 13, arranged to be turned inwardly so that its swinging edge will be held so as to bear against the periphery of a record of the largest size when disposed in the device snugly against the 65 plate 10. One size of the spacers 12 is adapted to fit snugly around the largest record, as shown in Figures 1, 2 and 4, and the tongue 13 is of a width to fit snugly between the side arms 14 of this larger 70 spacer. The tongue serves to prevent entrance of trash to the smaller records or spaces in the shipper, its outer end lying snugly between the arms of the spacer furthest removed from the plate 11 and fitting snugly between the plate 10 and the 75 arm portions of the second spacer from the plate 10, in the particular embodiment illustrated in Figures 3 and 4. Each of the plates 10 and 11, and the spacers 12 are 80 provided with apertures 15 at the corners, whereby suitable fasteners may be engaged therethrough to hold the parts in alined position.

In practice, the container may be made 85 up as needed, for each particular order of records to be shipped, a suitable supply of the different sizes of spacers being maintained on hand and sets of plates 10 and 11. When a shipment is to be made of a 90 number of records, which may be of various sizes, corresponding sizes of the spacers 12 are procured and secured between two plates 10 and 11, as indicated in Figures 3 and 4, by means of fasteners 17 which may 95 be of any usual form suitable for the purpose, and are formally represented in the present instance as looped wire fasteners as shown in Fig. 4. The spacers for larger records are disposed next to the plate 10, 100 and the smaller sizes progressively disposed toward the plate 11. The parts being assembled in proper order, the fastenings 17 are put in place adjacent the inner side 105 of the spacers and plates, being omitted adjacent the outer open side of the spacers until the records are put in place. The records may be inserted, after which the tongue

13 is bent inwardly, the inturned transverse edge portion abutting snugly against the periphery of the larger record at the far side of the shipper from the plate 11 5 on which the tongue is formed, after which the fastenings adjacent the open sides of the spacers are secured in place holding all in snug relation. For a package containing a large number of records, the plates 10 and 10 11 are centrally apertured to receive a center bolt 18 and wing nut 19, so that the parts may all be closely clamped together, affording mutual support, and preventing relative movement, such as might damage the 15 surfaces of the records.

It is to be noted that paste board is preferably used in the construction of these shippers, and such material would ordinarily not be strong enough to support the 20 weight of the record upon the bolt 18 without liability of the bolt working in the plates 10 and 11 so as to enlarge the apertures therein, if these disks were not supported at their edge portions, and it should be noted 25 that it is an advantage of my invention that I am able to provide an envelope-like form of shipper of a light material while yet supporting the parts without liability of damage to the container or its contents. By 30 the method of turning in the tongue 13, to engage the edges of the larger records, and by reason of the engagement of all other sides of the records good support is obtained for the records at all sides. The tongue 13 35 will support the larger record, and by use of the bolt and nut through the center, all records are clamped securely against the larger one, so that in the event that the package should fall upon that side upon 40 which the open side of the spacers are disposed, the weight of the small records will be supported upon the larger record which, resting upon the tongue 13 will prevent undue stresses from being communicated to 45 the small portion of material in the plates

10 and 11 which are clamped against the record.

In the event that but one record is to be shipped, the central screw and fastenings 17 may be dispensed with, and gummed 50 strips 20 engaged over the top and bottom edge portions of the plates 10 and 11, the tongue 13 being snugly held between the plates 10 and 11 and serving to prevent the record from striking against the binding strip at that side, making a secure package 55 by the use of very light material, obviating the necessity for the use of metal or excessively heavy boards.

It is an obvious advantage of the device 60 that it may be supplied to users ready-made—that is to say, with the spacers 12 secured between the plates in a suitable number, requiring only the insertion of the record disks through the open sides of the 65 spacers and the tongue element 13 turned inwardly and inserted as shown in Fig. 3 and the adjustment of the clamping device 18—19.

The spacers may be arranged to open on 70 different sides of the package if desired.

What is claimed:

A shipping envelope of the character described comprising front and back plates, a plurality of U-shaped spacers secured 75 therebetween, each spacer having arms extending across two sides of the envelope, the spacers being formed with bight portions of different sizes, each spacer opening on one side of the package whereby to receive snugly disk elements of respective sizes, and means to clamp the plates and interposed disks together.

In testimony whereof I have affixed my signature in presence of two witnesses.

THOMAS D. CURRIE.

Witnesses:

WILLIAM M. CRITTENDEN,
ANTHONY PELOSO.
